US0D1102382S

(12) **United States Design Patent** (10) Patent No.: **US D1,102,382 S**
(45) Date of Patent: ** Nov. 18, 2025

(54) **MEDICAL DEVICE CONNECTOR**

(71) Applicant: **Physio-Control, Inc.**, Redmond, WA (US)

(72) Inventors: **Ryan Bowman**, Richland, WA (US); **Zack Pahlman**, Redmond, WA (US); **Jeremy Wong**, Redmond, WA (US)

(73) Assignee: **Physio-Control, Inc.**, Redmond, WA (US)

(**) Term: **15 Years**

(21) Appl. No.: **29/878,072**

(22) Filed: **Jun. 15, 2023**

Related U.S. Application Data

(63) Continuation of application No. 29/808,259, filed on Sep. 17, 2021, now Pat. No. Des. 994,607, which is a continuation of application No. 29/708,322, filed on Oct. 4, 2019, now Pat. No. Des. 933,607.

(57) **CLAIM**

The ornamental design for a medical device connector, as shown and described.

DESCRIPTION

FIG. 1 is a front perspective view of a medical device connector;

FIG. 2 is a front view thereof;

FIG. 3 is a back view thereof;

FIG. 4 is a top view thereof;

FIG. 5 is a left side view thereof; and,

FIG. 6 is a right side view thereof.

The broken lines in the figures illustrate portions of the medical device connector that form no part of the claimed design.

1 Claim, 3 Drawing Sheets
